UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

MACHINE FOR MAKING COLLAPSIBLE-TUBE CAPS.

1,033,043.

Specification of Letters Patent.

Patented July 16, 1912.

Application filed September 5, 1911. Serial No. 647,750.

To all whom it may concern:

Be it known that I, RICHARD LESTER WILCOX, a citizen of the United States, residing at Waterbury, in the county of New Haven 5 and State of Connecticut, have invented certain new and useful Improvements in Machines for Making Collapsible-Tube Caps, of which the following is a specification, reference being had therein to the accompanying drawings.

My invention relates to a new and improved machine for making collapsible tube caps, and has for its object, among other things, to construct a machine for this purpose that will be entirely automatic in its operation and capable of producing these caps complete, including the thread, in substantially a single operation.

To these, and other ends, my invention 20 consists in the collapsible tube making machine, having certain details of construction and combinations of parts, as will be herein-after described and more particularly pointed out in the claims.

Referring to the drawings, in which like numerals of reference designate like parts in the several figures; Figure 1 is a front view of my improved machine, partly in section; Fig. 2 is an elevation of a fractional 30 portion of the punch and a finished cap with the die and bunter in section, all being in the relative positions occupied by them at the completion of the forming operation; Fig. 3 is a similar view with a modified 35 form of cap; Fig. 4 is a side elevation of my improved device; Fig. 5 is an enlarged sectional view of some of the parts, taken upon line A—B of Fig. 1; Fig. 6 is a fragmentary elevation of one end of the slide table with 40 the feed stop mechanism; Fig. 7 is a plan view of the slide table with the parts adjacent thereto; Fig. 8 is a sectional plan view of the punch block; Fig. 9 is an elevation of the slide cam; Fig. 10 is a fragmentary 45 plan view of the mechanism for rotating the punch with the mechanism adjacent thereto; Fig. 11 is an elevation of the feed slide cam; Fig. 12 is an elevation of the punch lifter cam, with the rock lever actuated thereby; 50 and Fig. 13 is an end view of the rack slide.

In the practice of my invention I provide a frame 1, which is mounted upon a suitable

standard 2, and within which is rotatably mounted the crank shaft 3, and the rock shaft 4, said crank shaft having a plate 5 55 upon one end thereof, and the rock shaft having a similar plate 6. These plates may be made integral with the shafts or separate, as desired. Slidable within the ways 7 is the upper gate 9, and slidable within the ways 8 is the lower gate 10, said upper gate being operated from the crank shaft 3 through the connection 11, and the lower gate 10 from the rock shaft 4 through the connection 12. A balance wheel 17, driven 65 in the usual manner by a belt, and mounted upon a shaft 18, upon which is fixed a pinion 19, that meshes into and drives a gear 20 fixed upon the shaft 3, is the means by which said crank shaft is rotated. Movement is imparted to the rock shaft 4 from the crank shaft 3 through the connection rods 13 and 14, the rod 13 being secured at its upper end to the plate 5 and the rod 14 at its lower end to the plate 6, and both connected at their inner ends to an oscillating plate 15, that is mounted upon a fixed stud 16.

Within the lower gate 10 is the bunter collet 21 that is secured in its several adjustable positions by the nuts 22, which are threaded on the shank of said collet and contact with the opposite faces of the opening 23 in said gate (see Fig. 5). Held within the said collet by a screw 24, or other similar means, is the bunter 25. The upper face of the bunter is usually concaved, as shown in Figs. 2 and 3, but it may be made in any other desired shape, and provided with such recesses or depressions as may be necessary to produce the proper form or design for the top of the cap.

Within the upper gate 9 is the spindle holder 26, that is secured in its adjusted positions by the nuts 27, which are threaded upon the shank thereof and abut against the opposite faces of the slot 28 in said gate. Adjustable transversely in the head of said spindle holder is the block 29, which is held against movement in its adjusted position 95 by the screws 30—30, which are threaded in the gate 9, with their heads impinging against the opposite ends of said block. The punch block is designated by the nu-

meral 31 and is secured to the frame 1 by the bolts 32, and has a limited lateral adjustment through the screws 33, which are threaded in the frame 1, with their heads impinging against the opposite sides of said block (Fig. 8). Fixed to the front of said block is the cap 34, and mounted in said cap and a bushing 35 in said block, so as to have a rotary and endwise movement therein, is the spindle 36, which is constructed with a toothed portion 37, an annular groove 38, and a shank portion that projects through the block 29 into the opening in the lower end of the holder 26, of slightly larger diameter than the spindle shank. A punch 39 is secured in the spindle 36, and is formed with a thread at its lower end, of the same pitch as the thread upon the inside of the finished cap. A limited lateral adjustment of the position of the spindle 36 is made possible by shifting the block 29 within the spindle holder 26, through the manipulation of the screws 30, and of the punch block 31, through the manipulation of the screws 33.

The mechanism for imparting a rotary movement to the spindle 36 comprises a slide bracket 40 that is secured to the frame 1, and having mounted therein a rack slide 41, the teeth of which mesh into the teeth of a pinion 42, rotatably mounted upon a stud 43 fixed in said bracket 40 and the cap 44 fixed thereto; and a gear 45 fixed to the pinion 42, the teeth of which mesh into the teeth of a pinion 46, rotatable upon a stud 47, also fixed in the bracket 40 and cap 44 and having connected therewith a gear 48, the teeth of which mesh into the teeth on the toothed portion 37 of the spindle 36. A reciprocating movement is imparted to the rack slide 41 and a rotary movement to the spindle 36 through a cam 49 that is fixed upon a shaft 50, rotatably mounted in the frame 1, and having a gear 51 thereon, that is driven from the pinion 19, a roll 52 on the rack slide 41 entering the cam groove 53 in the cam 49. A downward movement is given the spindle 36 by the gate 9, but it is moved upwardly, independently thereof, through the rock lever 54, that is pivotally secured to the frame 1, and having a yoke 55 mounted in its inner end, which projects into the annular groove 38 in the spindle 36. The spring 56 connecting said rock lever with a fixed stud on the side of the frame 1, always exerts its pull so as to move the spindle 36 upwardly, but, if perchance the spring should break, I have provided mechanical means for accomplishing this purpose, which means comprises a cam 57, fixed to the shaft 3, a rock lever 58, pivotally secured to the frame 1 by a stud 59, and having a cam roll 60 rotatably mounted therein upon the stud 61, said lever being connected with the block 62 secured to the outer

end of the rock lever 54 by the adjustable connecting rod 63. The spring 56, which actuates the lever 54, is only of sufficient strength to raise the spindle 36 without creating undue pressure upon the thread in the finished cap, while the same is being withdrawn therefrom. For this reason the spindle is not moved upwardly by a positive cam motion, which would be liable to strip the thread.

Fixed to the frame 1, between the sides thereof, is the slide table 64, within which is mounted the slide 65, beneath the caps 103, and secured in said slide by the screws 67 is the die 66. This method of securing the die in a fixed position is only one of many ways by which the same result may be accomplished, and I do not therefore limit myself to this form of securing means.

The bunter and die, when together, form substantially a two-part die, separable upon a line at a right angle to the axis of said bunter and the opening in said die.

A reciprocating movement is imparted to the slide 65 from the cam 68 that is fixed upon the shaft 50; a rock arm 69 secured to the frame 1 upon the stud 70 and having a cam roll 71 thereon, which enters the groove 72 in said cam 68; the bracket 73 fixed to the slide 65 and having a stop screw 74 therein, which abuts against the outer end of the table 64, to limit the inward movement of said slide; and a connecting rod 75 hinged at one end to the bracket 73, and at the other end secured to the free end of the rock arm 69 by the block 76, which is adjustably secured to said rock arm by the bolt 78 that passes through the slot 79 in said arm, and within which the connecting rod 75 has an endwise adjustment through the manipulation of the nuts 77. Also slidably mounted in the said slide table, under the caps 104, is the plate 80 that derives its movement in one direction through the action of the spring 81 connected with the cap 34 and the arm 82 fixed on said plate. Its movement in the other direction is derived from the cam 83 fixed upon the shaft 3, through a rock lever 84 pivotally secured to the frame 1, having a roll 85 thereon that rests upon the periphery of said cam, a rock shaft 86 mounted in the depending ears 87 upon the slide table 64, having an arm 88 fixed thereon that is connected with the rock lever 84 through the connection rod 89 that has a limited adjustment in the direction of its length by the turn buckle 90, an arm 91 also fixed to the shaft 86, and a link 92 connected with said arm 91 and the yoke stud 93 fixed in said plate 80. Pivotally connected to the inner end of the plate 80 by the screws 95 are the fingers 94 that are provided with curved recesses 96 near their outer free ends, which, when the fingers are together, with their inner faces abutting against each other,

form a circle slightly less than the diameter of the blank to be operated upon. Said fingers are drawn toward each other by the spring 97 and are prevented from moving 5 out of their central position by the stud 98, which is fixed in the plate 80 and projects between the inner faces of said fingers.

Secured in the lug 99, integral with the cap 34, is the tube holder 100, and fixed in 10 the upper end thereof is the feed tube 101. In the outer position of the plate 80, the curved recesses 96 in the fingers 94 are concentric with the tube holder 100, the fingers being held open or apart, as shown in Fig. 15 7, by the contact of the pins 102 in said fingers with the outside of said tube holder. In the inner position of said plate the recesses 96 are concentric with the spindle 36.

I have provided means for holding the 20 feed slide 80 against movement, so as to stop the feeding of blanks when desired, which means comprises a stop lever 105 fixed on the rock shaft 86, and movable in the path of the stop arm 106, pivotally secured to the 25 side of the feed table 64 on the stud 107, a stud 108 fixed in said table, and by reason of its engagement of the opposite ends of the groove 109 in the outer edge of said stop arm, limits the movement thereof, and a 30 spring 110 holding said stop arm in either of its extreme positions.

When the plate 80 is moving so as to feed blanks, the end of the lever 105 and the stop arm 106 are in the relative positions shown 35 by broken lines in Fig. 6. To stop the movement of said plate, the arm 106 is brought into the path of the end of the lever 105 by moving the same manually from the position shown by broken lines to the position shown 40 by full lines, and for convenience, a handle 111 is fixed thereto for this purpose, which also furnishes convenient means to secure one end of the spring 110.

The knockout mechanism comprises a slide 45 112 mounted in the punch block 31 having a knockout pin 113 secured in its lower end, a lever 114 pivotally mounted in the bracket 115 that is fixed to the slide bracket 49, and having a roll 116 upon its outer end, which 50 enters a groove in the face of the cam 117, that is fixed upon the shaft 50. The knockout punch is located coincident with the upper end of the discharge tube 118 fixed to the underside of the slide table 64.

In operation, the blanks, in the form of 55 circular disks, are dropped into the feed tube 101, from which they enter the tube holder 100 and successively rest upon the top of the slide 65 between the recesses 96 of the fingers 94. As each blank successively drops into this position the plate 80 advances, and as the pins 102 are released 60 from their engagement with the lower end of the tube holder 100, the spring 97 draws 65 the said fingers together and holds the blank

tightly in the recesses 96 and it is thus carried into a position under the spindle 36. At this time the lower gate moves upwardly and the bunter 25 moves into the position shown in Figs. 2, 3 and 5, that is, with its upper surface in contact with the lower face of the die 66. At the same time the spindle 70 36 is moved downwardly and forces the disk through the opening in the die and forms the completed blank, as shown in Figs. 2 75 and 3. As soon as the punch 39 engages the blank the slide plate 80 is withdrawn and the fingers 94 are again brought into register with the tube holder 100, and receive another blank. It will be observed that during the movement of the slide 80 the blanks do not fall out of the tube holder, as the lower blank rests upon the top of the fingers 80 94. After the blank is formed, the upper gate moves upwardly without the spindle 85 36, which is returned by the action of the lever 54, as above described, and while being returned is rotated through the engagement of the gear 48 with the toothed portion 37, this action unscrewing the punch from the thread formed in the cap. While these parts are moving, as just described, the lower gate, and with it the bunter, is moved to its down position. After the punch has been withdrawn so that the lower 90 end thereof is above the top of the slide 65, movement is imparted to said slide so as to bring the die 66 into register with the knockout pin 113, which then moves downwardly and knocks the finished cap out of 95 the die into the discharge tube 118, from which it drops into a receptacle conveniently arranged to receive it. The slide 65 is now returned to the position wherein the die is in register with the spindle 36. The 100 bore at the lower end of the die 66 is provided with grooves so as to produce a knurled periphery upon the finished cap 105 and the lower edge of said die is coincident with the edge of said knurled portion, so that there will be no marring of said knurled portion by reason of the failure of the bunter to register exactly with the said die.

In Fig. 2 I have shown one type of cap 115 that may be constructed in my machine, and in Fig. 3 a modified form thereof with an inwardly projecting valve, but other forms may be produced equally as well by merely changing the form of the lower end of the 120 punch and the upper end of the bunter.

There are minor changes and alterations that can be made within my invention, aside from those herein suggested, and I would therefore have it understood that I do not 125 limit myself to the exact construction herein shown and described; but claim all that falls fairly within the spirit and scope of my invention.

Having described my invention, what I 130

claim as new, and desire to secure by Letters Patent, is:—

1. The combination with a die, the opening therethrough being enlarged at that end thereof opposite to the end through which the blank enters said opening; of a movable bunter arranged so as to abut against the face of said die and close the said opening at its enlarged end; and a punch movable in and out of said die and entering said opening at its smaller end, the arrangement and operation of the several parts being such that at the completion of the movement of said punch toward said bunter, a cup or similar structure will have been formed within said die and in part surrounding said punch, with a portion thereof of larger diameter than the body thereof, said enlarged portion being at the end of said die opposite to the end through which the blank enters.

2. In a machine of the character described, the combination with a die, having an opening therethrough, enlarged at that end thereof opposite to the end through which the blank enters said opening; of a movable bunter, arranged so as to abut against the face of said die and close the said opening at its enlarged end; and a punch, threaded at its lower end, movable in and out of said die and entering said opening at its smaller end.

3. The combination with a two-part die, one of said parts having an opening therethrough that is enlarged at that end thereof opposite to the end through which the blank enters said opening, and the other part of said die being movable toward and away from the first part and closing said enlarged open end; and a punch movable in and out of said opening through its smaller end and toward and away from the said second part of said two-part die, the arrangement and operation of the several parts being such that at the completion of the movement of said punch toward the second part of said two-part die, a cup or similar structure will have been formed within said die and in part surrounding said punch, with a portion thereof of larger diameter than the body thereof, said enlarged portion being at the end of said die opposite to the end through which the blank enters.

4. In a machine of the character described, the combination with a die, having an opening therethrough, said opening being enlarged at the bottom thereof; of a bunter arranged so as to abut against the bottom face of said die and close the opening therethrough; a punch movable in and out of said die toward and away from said bunter; means for moving said punch into said die without rotation; and means for moving said punch out of said die and im-

parting a rotary movement thereto at one and the same time.

5. In a machine of the character described, the combination with a die, having an opening therethrough, said opening being enlarged at the bottom thereof; of a bunter arranged so as to abut against the bottom face of said die and close the opening therethrough; a punch movable in and out of said die toward and away from said bunter; means for moving said punch into said die without rotation; and yielding means for moving said punch out of said die and imparting a rotary movement thereto at one and the same time.

6. In a machine of the character described, the combination with a die, having an opening therethrough, said opening being enlarged at the bottom thereof; of a bunter arranged so as to abut against the bottom face of said die and close the opening therethrough; a punch movable in and out of said die toward and away from said bunter; means for moving said punch into said die without rotation; a spring actuated lever, for withdrawing said punch from said die; and means for rotating said punch while being withdrawn.

7. In a machine of the character described, the combination with a die, having an opening therethrough, said opening being enlarged at the bottom thereof; of a bunter arranged so as to abut against the bottom face of said die and close the opening therethrough; a punch movable in and out of said die toward and away from said bunter; means for moving said punch into said die without rotation; a spring actuated lever, for withdrawing said punch from said die; and means for withdrawing said punch from said die if said spring should break, comprising a cam, a rock lever, and a connection between said levers.

8. In a machine of the character described, the combination with a solid die, having an opening therethrough enlarged at its lower end; of a bunter movable toward and away from said die, and when in contact therewith, closing said enlarged open end; a punch, that enters said die without rotation and rotates while being withdrawn therefrom; and means for ejecting the finished article from said die.

9. In means for forming metal caps, or similar articles, having an enlargement adjacent to the end thereof, and an internally threaded shank, the combination with a solid die, having an opening therethrough of substantially the same shape as a section of said article up to the end of said enlargement, said enlarged portion of said opening being at the lower end of said die; of a bunter, having a depression in the upper face thereof corresponding in shape with the end of said article; means for moving

said bunter toward and away from said die; and a punch, having a threaded lower end, movable into said die without rotation, and withdrawn therefrom with a rotary movement.

10. In a machine of the character described, the combination with a die; of a punch; means for moving said punch into said die without rotation; and means for rotating said punch while the same is being withdrawn from the said die, said means comprising a reciprocating rack and intermediate gears and pinions between said rack and said punch.

15. 11. In a machine of the character described, the combination with a slide; of means for imparting a reciprocatory movement thereto at predetermined periods; a die fixed therein; a plate, having a reciprocatory movement parallel with said slide but independently thereof; a spindle mounted in a fixed part; a punch connected with said spindle; means for moving said spindle in one direction without rotation; means for rotating said spindle while being moved in the opposite direction; means, for delivering blanks to said slide; carrier fingers pivotally connected with said plate, having recesses near their outer free ends; means for separating said fingers to receive a blank from said blank delivering means; a bunter, with its axis substantially coincident with the axis of said punch; and means for moving the same toward and away from said die.

35. 12. In a machine of the character described, the combination with a die; of a punch; means for moving said punch into said die without rotation; and means for rotating said punch while the same is being withdrawn from the said die.

40. 13. In a machine of the character described, the combination with a die; of a punch; means for moving said punch into said die without rotation; and cam means for rotating said punch while the same is being withdrawn from the said die.

45. 14. The combination with a die, having an opening therethrough, enlarged at one end; of a bunter; a punch; means for moving said punch into and out of the opening in said die, and through the smaller end thereof; and means for actuating said

bunter, whereby it may be moved toward and away from said die and held against the face thereof and cover said opening at its enlarged end while said punch is moving in said opening in one direction, whereby the metal as it is forced through said opening by said punch will be spread outwardly to fill the enlarged portion of said opening after it contacts with said bunter.

50. 15. The combination with a die, having an opening therethrough, enlarged at one end; of a bunter; a punch; means for moving said punch into and out of the opening in said die, and through the smaller end thereof; means for actuating said bunter whereby it may be moved toward and away from said die and held against the face thereof and cover the said opening at its enlarged end while said punch is moving in said opening in one direction, whereby the metal as it is forced through said opening by said punch will be spread outwardly to fill the enlarged portion of said opening after it contacts with said bunter; and means for ejecting the finished articles from the die, at the end thereof opposite to the end from which the blank enters said die.

55. 16. In a machine for forming, from a piece of flat metal, cups, or similar articles, having a plurality of outside diameters, the larger of said diameters being adjacent to the end thereof opposite to the open end, the combination with a die having an opening therethrough, enlarged at that end thereof opposite to the end through which the blank enters said opening; of a movable bunter arranged so as to abut against the face of said die and close the said opening at its enlarged end; and a punch movable in and out of said die and entering the said opening at its smaller end, so that at the completion of its stroke toward said bunter, the said cup is completed, with that portion thereof having the enlarged diameter adjacent to the end of said punch and that portion thereof of smaller diameter surrounding said punch.

60. In testimony whereof I affix my signature in presence of two witnesses.

RICHARD LESTER WILCOX.
